UNITED STATES PATENT OFFICE.

THOMAS CLARKSON, OF GALLEYWOOD, ENGLAND, ASSIGNOR TO NATIONAL STEAM CAR COMPANY, LIMITED, OF CHELMSFORD, ENGLAND.

APPARATUS FOR THE CONTROL OF STEAM-GENERATORS.

1,189,429.

Specification of Letters Patent.

Patented July 4, 1916.

Application filed July 17, 1914. Serial No. 851,539.

To all whom it may concern:

Be it known that I, THOMAS CLARKSON, subject of the King of England, residing at Gallywood, Essex, in England, have invented certain new and useful Apparatus for the Control of Steam-Generators, of which the following is a specification.

This invention relates to the control of steam generators more particularly those intended for use on motor road vehicles and heated by solid fuel and has for its object to regulate the supply of fuel to the grate and simultaneously control the supply of water to the generator.

According to this invention solid fuel preferably in the form of coke which is contained in one or more bunkers is caused to pass from the bottom of each bunker to the furnace by means of reciprocating push-rods or the like to which motion is imparted preferably from a steam-operated water pump the supply of steam to which is controlled, conveniently automatically in accordance with the variations of the water level in the generator. The supply of fuel to the grate is thus regulated simultaneously with the supply of water to the generator and in accordance with the requirements of the latter.

In the accompanying drawings which illustrate by way of example the application of the invention to a motor road vehicle, Figure 1 is a side elevation of the fore part of the motor road vehicle showing a considerable portion of the mechanism comprised in the present invention. Fig. 2 is a vertical section through the generator on the line 2—2 in Fig. 1 looking toward the front of the vehicle and drawn on a larger scale. Fig. 3 is a part vertical section through the generator also on the line 2—2 in Fig. 1 but looking toward the rear of the vehicle so as to show parts of the mechanism by which motion is imparted from the pump to the push-rods and other features. Fig. 4 is a sectional elevation of the float-operated automatic control device.

Like letters indicate like parts throughout the drawings.

The generator to which the present invention is preferably applied is of the vertical semi-flush type and is inclosed in a casing A. Outside this casing and on opposite sides thereof are arranged two bunkers B

adapted to contain solid fuel which is preferably coke graded to a suitable size. In the upper part of each bunker is a charging opening B' provided with a suitable closure and in the lower part of the outer wall is an inspection opening B² with hinged cover. The lower part of each bunker is formed as a chute B³ which leads past the lower edge A' of the generator casing on to a dead plate C. The grate is formed of fixed and movable bars. Preferably two movable bars D are provided so mounted as to be capable of being rocked in some convenient manner as hereinafter described. The fixed fire-bars D' are of some suitable construction and disposed between the rocking bars D and the dead plates C. The shape, disposition and construction of these fire-bars and dead plates may vary to meet requirements and the nature of the generator to which the invention is applied. An ashpan E is disposed beneath the grate. The generator is supported by suitable means on the side members F of the chassis.

In the lower part B⁴ of the outer wall of each bunker is formed a series of holes B⁵ which holes, as is apparent from Fig. 1, are arranged in two horizontal rows, one row being slightly above the other. Through each of these holes freely passes a push-rod G, the outer end of which is pivotally connected to a lever H secured on a rockshaft J. This rockshaft is mounted in bearings J' on the chassis members F.

A steam-operated pump K of some suitable type is carried on a bracket from one of the chassis members F. This member also has mounted on it some convenient position intermediate between the pump K and the lever H on the rockshaft, a bracket L which carries a stud L' projecting horizontally at right angles to the axis of the rockshaft J. On this stud is freely pivoted a two-armed lever M M'. The upper arm M' carries a pawl M² while the lower arm M is connected by a rod M³ with the piston rod K' of the pump K. The stud L' also carries loose upon it a ratchet wheel N and an eccentric or crank N' which is formed integral with the ratchet wheel. The pawl M² engages the ratchet wheel N so that this wheel and the eccentric are intermittently rotated as the lever M' is oscillated by the operation of the pump. A pawl L² carried

by the stud L' insures the rotation of the ratchet wheel being continuously in one direction.

The eccentric has a rod N² the end of 5 which is connected by a ball joint with the end of a lever J² secured on the rockshaft J. Thus as the ratchet wheel and the eccentric rotate the shaft J is rocked through the lever J² and the push-rods G are reciprocated by means of the levers H.

To enable the push-rods G to be reciprocated and the pump operated by hand on occasion, a two-armed lever O is mounted loosely on a pivot carried by a bracket disposed at some point between the pump and the bracket L. One end of this lever O is forked and engages a pin on the rod M³ while the upper end is shaped to receive a socket on the end of a detachable hand lever O'. By means of this lever the pump piston can be reciprocated and the lever M swung to and fro so that water can be fed into the generator and at the same time the push-rods actuated.

It is obvious that by controlling the supply of steam to the pump K the operation of the push-rods G will be regulated simultaneously with the supply of water to the generator and thus the control of the fuel feed and water feed will be simultaneous. The supply of steam to the pump can be controlled by hand but preferably this control is automatic and effected by the variations in the level of the water in the generator. A device suitable for this purpose is shown in Fig. 1 on the rear side of the generator and is also illustrated on a larger scale in Fig. 4. This device comprises a cylindrical drum P which is in communication by a pipe P' with the steam space of the generator and also communicates by a pipe P² with the water space. Within the drum P is a cylindrical float Q which is provided with pivot or gudgeon pins Q' and Q². One of these pins Q² rests in a bearing in one of the end covers of the drum P but does not pass through this cover but the other pin Q' passes out through a stuffing box P³ and has secured on its outer 45 end a two-armed lever R. One arm of this lever is formed as a handle while the other arm is connected by a link S to a lever T on the spindle of a screw down steam valve T' disposed in the pipe U which supplies steam to the pump K.

It will be apparent that as the level of the water in the generator rises or falls so will the movement of the float Q operate the steam valve T' through the levers R, T and link S and thus 50 control the supply of steam to the pump. The handle on the lever R enables the float and other parts of the mechanism to be operated by hand when desired to test their free working or to control the pump under 55 special circumstances.

The mechanism for rocking the fire-bars D may be as shown in Fig. 3. Connected to the end of each bar is a lever D² these levers being connected by a link D³. One of these levers D² is extended and provided with a handle D⁴ which as shown in Fig. 1 is disposed within reach of the driver who can thus rock the bars D from time to time. If desired the rocking can be effected automatically by providing one of the bars with 70 a second lever D⁵ which is connected by a link D⁶ with a lever D⁷ on the rock-shaft J. The rocking of the bars will thus take place in consonance with the feeding of the fuel. 75

It is obvious that reciprocation of the push rods G can equally in accordance with this invention be effected by mechanism other than that described in detail above. Thus in place of the rock-shaft J with levers H the push rods G may be connected to a 80 shaft provided with cranks or eccentrics the rotation of this shaft being effected from the pump by suitable mechanism. This mechanism may comprise bevel wheels on the crank shaft and a stud L respectively 85 which will serve to convert the reciprocation to the pump into intermittent rotation of the crank shaft.

What I claim as my invention and desire to secure by Letters Patent is:—

1. In apparatus for the control of steam generators the combination of a generator having a grate for burning solid fuel, a bunker, a plurality of push-rods each of which passes through a hole in the bunker wall in such position as to operate on the fuel lying in the lower part of the bunker for transferring the solid fuel from the bottom of the bunker on to the grate, a steam-operated feed pump for the generator, an operative connection between this pump and the push-rods, and means for automatically controlling the supply of steam to the pump in accordance with the variations of the level of the water in the 100 generator.

2. In apparatus for the control of steam generators the combination with a generator having a grate for burning solid fuel, a bunker adjacent to the generator with a chute at its lower end leading on to the grate, a plurality of push-rods each of which passes freely through a hole in the bunker wall in such a position as to operate on the fuel lying in the lower part of the bunker 115 and means for reciprocating the push-rods and imparting a rocking movement thereto.

3. In apparatus for the control of steam generators the combination with a generator having a grate for burning solid fuel, a bunker adjacent to the generator with a chute at its lower end leading on to the grate, a plurality of push-rods each of which passes freely through a hole in the bunker wall in such a position as to operate on the 125 130

fuel lying in the lower part of the bunker, means for reciprocating the push-rods and means for automatically controlling the mechanism by which the push-rods are reciprocated in accordance with the variations in the level of the water in the generator as set forth.

4. In apparatus for the control of steam generators the combination with a generator having a grate for burning solid fuel, a bunker adjacent to the generator with a chute at its lower end leading on to the grate, a plurality of push-rods each of which passes freely through a hole in the bunker wall in such a position as to operate on the fuel lying in the lower part of the bunker, a steam-operated feed pump for the generator, means actuated by the feed pump for reciprocating the push-rods and means for controlling the supply of steam to the pump in accordance with the variations in the level of the water in the generator.

5. In apparatus for the control of steam generators the combination with a generator having a grate for burning solid fuel, a bunker adjacent to the generator with a chute at its lower end leading on to the grate, rockable grate bars, a plurality of push-rods each of which passes freely through a hole in the bunker wall in such a position as to operate on the fuel lying in the lower part of the bunker, a steam-operated feed pump for the generator, means actuated by the feed pump for simultaneously reciprocating the push-rods and rocking the grate bars and means for automatically controlling the supply of steam to the pump in accordance with the variations in the level of the water in the generator as set forth.

6. In apparatus for the control of steam generators the combination of a generator having a grate for burning solid fuel, a bunker adjacent to the generator with a chute at its lower end leading on to the grate, a rockshaft mounted in bearings outside the bunker wall, levers on this rockshaft, a push rod pivoted to the end of each lever and passing freely through a hole in the bunker wall in such a position as to operate on the fuel lying in the lower part of the bunker, and means for rocking the rockshaft, as set forth.

55 7. In apparatus for the control of steam generators the combination of a generator having a grate for burning solid fuel, a bunker adjacent to the generator, with a chute at its lower end leading on to the grate, a rockshaft mounted in bearings outside the bunker wall, levers on this rockshaft, a push-rod pivoted to the end of each lever and passing freely through a hole in the bunker wall in such a position as to operate on the fuel lying in the lower part of the bunker,

means for rocking the rockshaft, and means automatically actuated for controlling the rocking mechanism as set forth.

8. In apparatus for the control of steam generators the combination of a generator 70 having a grate for burning solid fuel, a bunker adjacent to the generator, with a chute at its lower end leading on to the grate, a rockshaft mounted in bearings outside the bunker wall, levers on this rock- 75 shaft, a push-rod pivoted to the end of each lever and passing freely through a hole in the bunker wall in such a position as to operate on the fuel lying in the lower part of the bunker, mechanism for rocking the rock- 80 shaft and means automatically actuated by the variations in the water level in the generator for controlling the rocking mechanism as set forth.

9. In apparatus for the control of steam 85 generators the combination of a generator having a grate for burning solid fuel, a bunker adjacent to the generator with a chute at its lower end leading on to the grate, a rockshaft mounted in bearings outside the 90 bunker wall, a plurality of push-rods each pivoted to the end of a lever on the rock- shaft, a plurality of holes in the outer wall of the bunker each hole adapted for the free passage therethrough of a push-rod, a 95 steam operated feed pump for the generator, means actuated by the feed pump for rocking the rockshaft, and means for controlling the supply of steam to the pump as set forth.

10. In apparatus for the control of steam generators the combination of a generator having a grate for burning solid fuel, a bunker adjacent to the generator terminating at its lower end in a chute leading on 105 to the grate, a rockshaft mounted in bearings outside the bunker wall, a plurality of push-rods each pivoted to the end of a lever on the rockshaft and each push-rod passing freely through a hole in the lower part of the outer bunker wall, a steam-operated 110 feed pump for the generator, a fixed stud on which freely pivots a lever carrying a pawl, a ratchet wheel integral with an eccentric and both freely rotatable on the fixed stud, 115 a connection between a moving part of the pump and the free end of the pivoted lever, means for imparting motion from the eccentric to the rockshaft, and means for controlling the supply of steam to the pump as 120 set forth.

11. In apparatus for the control of steam generators the combination of a generator having a grate for burning solid fuel, a bunker adjacent to the generator terminating at its lower end in a chute leading on to the grate, a rockshaft mounted in bearings outside the bunker wall, a plurality of push rods each pivoted to the end of a lever on the rockshaft and each push-rod passing 130

- freely through a hole in the lower part of the outer bunker wall, a steam-operated feed pump for the generator, means actuated by the feed pump for rocking the rockshaft, 5 and means for automatically controlling the supply of steam to the pump in accordance with the variations in the level of the water in the generator as set forth.
12. In apparatus for the control of steam generators the combination of a generator having a grate for burning solid fuel, a bunker adjacent to the generator terminating at its lower end in a chute leading to the grate, rockable grate bars, a rockshaft 10 mounted in bearings outside the bunker wall, a plurality of push-rods each pivoted to the end of a lever on the rockshaft and each push-rod passing freely through a hole in the lower part of the outer wall of a bunker, a steam-operated feed pump for the generator, a fixed stud on which freely pivots a lever carrying a pawl, a ratchet wheel integral with an eccentric and both freely rotatable on the fixed stud, a connection between a moving 15 part of the pump and the free end of the pivoted lever, an eccentric strap and a connection therefrom to the rock-shaft and means for controlling the supply of steam to the pump as set forth.
13. In apparatus for the control of steam generators the combination of a generator having a grate for burning solid fuel, bunkers adjacent to the generator, each bunker 20 terminating at its lower end in a chute leading on to the grate, a rockshaft mounted in bearings outside the wall of each bunker, a coupling between the rockshafts, a plurality of push-rods each pivoted to the end of a lever on a rockshaft and each push-rod 25 passing freely through a hole in the lower part of the outer wall of a bunker, and means for rocking the rockshafts as set forth.
14. In apparatus for the control of steam generators the combination of a generator having a grate for burning solid fuel, bunkers adjacent to the generator, each bunker 30 terminating at its lower end in a chute leading on to the grate, a rock-shaft mounted in bearings outside the wall of each bunker, a coupling between the rockshafts, a plurality of push-rods each pivoted to the end of a lever on a rockshaft and each push-rod 35 passing freely through a hole in the lower part of the outer wall of a bunker, and means for rocking the rockshafts as set forth.
15. In apparatus for the control of steam generators the combination of a generator having a grate for burning solid fuel, bunkers adjacent to the generator, each bunker 40 terminating at its lower end in a chute leading on to the grate, a rockshaft mounted in bearings outside the wall of each bunker, a coupling between the rockshafts, a plurality of push-rods each pivoted to the end of a lever on a rockshaft and each push-rod 45 passing freely through a hole in the lower part of the outer wall of a bunker, and means for rocking the rockshafts as set forth.
16. In apparatus for the control of steam generators the combination of a generator having a grate for burning solid fuel, bunkers adjacent to the generator, each bunker 50 terminating at its lower end in a chute leading on to the grate, a rock-shaft mounted in bearings outside the wall of each bunker, a coupling between the rockshafts, a plurality of push-rods each pivoted to the end of a lever on a rockshaft and each push-rod 55 passing freely through a hole in the lower part of the outer wall of a bunker, and means for rocking the rockshafts as set forth.

the water level in the generator for controlling the rocking mechanism as set forth.

15. In apparatus for the control of steam generators the combination of a generator 60 having a grate for burning solid fuel, bunkers adjacent to the generator each bunker terminating at its lower end in a chute leading on to the grate, a rockshaft mounted in bearings outside the wall of each bunker, a 65 coupling between the rockshafts, a plurality of push-rods each pivoted to the end of a lever on a rock-shaft and each push-rod passing freely through a hole in the lower part of the outer wall of a bunker, a steam- 70 operated feed pump for the generator, a fixed stud on which freely pivots a lever carrying a pawl, a ratchet wheel integral with an eccentric and both freely rotatable on the fixed stud, a connection between a moving 75 part of the pump and the free end of the pivoted lever, an eccentric strap and a connection therefrom to the rock-shaft and means for controlling the supply of steam to the pump as set forth.

16. In apparatus for the control of steam generators the combination of a generator having a grate for burning solid fuel, bunkers adjacent to the generator each bunker terminating at its lower end in a chute leading on to the grate, a rockshaft mounted in bearings outside the wall of each bunker, a coupling between the rockshafts, a plurality of push-rods each pivoted to the end of a lever on a rockshaft and each push-rod 80 passing freely through a hole in the lower part of the outer wall of a bunker, a steam-operated feed pump for the generator, a fixed stud on which freely pivots a lever carrying a pawl, a ratchet wheel integral with an eccentric and both freely rotatable on the fixed stud, a connection between a moving 85 part of the pump and the free end of the pivoted lever, an eccentric strap and a connection therefrom to the rockshaft, and means for automatically controlling the supply of steam to the pump in accordance with variations of the level of the water in the generator as set forth.

In testimony whereof I have signed my 105 name to this specification in the presence of two subscribing witnesses.

THOMAS CLARKSON.
